UNITED STATES PATENT OFFICE.

JAMES C. BARR AND VIRGIL EDSON BARR, OF AMANDA, OHIO.

SASH-CORD FASTENER.

SPECIFICATION forming part of Letters Patent No. 681,385, dated August 27, 1901.

Application filed June 25, 1901. Serial No. 65,985. (No model.)

To all whom it may concern:

Be it known that we, JAMES C. BARR and VIRGIL EDSON BARR, citizens of the United States, residing at Amanda, in the county of 5 Fairfield and State of Ohio, have invented a new and useful Sash-Cord Fastener, of which the following is a specification.

This invention relates to sash-cord fasteners, and has for its object to provide certain 10 improvements in the connection between a sash-cord and the sash, whereby the cord may be readily attached and detached without withdrawing fastening devices from the sash and thereby without damage to the sash and 15 cord. It is furthermore designed to provide an improved socket for application to the sash, which is arranged to be maintained tightly thereon, and also to improve the fastening device, which is carried by the cord 20 and arranged for detachable engagement with the socket.

With these and other objects in view the present invention consists in the combination and arrangement of parts, as will be herein- 25 after more fully described, shown in the accompanying drawings, and particularly pointed out in the appended claims, it being understood that changes in the form, proportion, size, and minor details may be made 30 within the scope of the claims without departing from the spirit or sacrificing any of the advantages of the invention.

In the drawings, Figure 1 is a perspective view of one corner portion of a window-sash 35 having the present invention applied thereto. Fig. 2 is an elevation thereof. Fig. 3 is a central longitudinal sectional view. Fig. 4 is a detail perspective view of the fastening device for application to the end of a sash- 40 cord. Fig. 5 is a detail perspective view of the socket for application to a window-sash. Fig. 6 is a detail view showing the manner of clamping the fastening device upon a cord.

Referring to the drawings, 1 designates the 45 upper corner portion of an ordinary window-sash, which is provided in its vertical edge with the usual longitudinal groove 2, terminating at its inner end in an enlarged recess or seat 3, the groove being for the reception 50 of the sash-cord 4 in the usual manner. These parts are common and well known and

have been shown to adequately illustrate the present invention.

In carrying out the present invention there is provided a metallic socket 5 in the form of 55 a cylinder or tube, which is split longitudinally, as at 6, to form a spring-socket that is designed to fit snugly within the recess or seat 3 in the edge of the window-sash and by reason of its spring to maintain a snug fit 60 therein. The outer end of the tubular socket is partly closed by means of the diametrically opposite ears or projections 7, that are directed inwardly in opposite directions across the outer end of the socket and terminate 65 short of each other, thereby providing an inverted substantially T-shaped slot or opening in the outer end of the socket. The upper portion of the outer edge of the socket is provided with a longitudinal notch 8, which 70 is diametrically opposite the longitudinal slot 6, which extends from end to end of the socket. This socket is driven into the correspondingly-shaped recess 3 in the sash, so that its outer end may be flush with the outer edge of the 75 sash, whereby the socket projects across the inner end of the groove in the sash and the notched portion 8 is disposed to lie at the said inner end of the groove. In placing the socket in the sash it is compressed as much 80 as possible, so as to freely enter the recess, after which it is permitted to spring outwardly, and thereby snugly fit the recess, so as to obviate the employment of additional fastenings to secure the socket in place. 85

The fastening, which is applied to the end of the sash-cord, consists of a laterally-bowed shank portion 9, which has one end, which is normally its lower end, provided with an enlarged circular head 10, that lies in substantially the same plane with the shank and is connected thereto by means of a reduced neck portion 11, the opposite edges of the shank being provided with staggered and laterally-projected ears 12, which are capable of being 95 bent around the sash-cord, as shown in Fig. 6. The shank portion is provided with a plurality of pointed spurs or prongs 13, which are struck therefrom and extend or incline toward the head portion 10 upon what may be 100 termed the "inner" side of the shank, so as to take into the cord, and thereby prevent the

latter from slipping endwise from the fastening. It will be observed that the head and neck portion project below the lower end of the cord, so that the fastening may be turned 5 edgewise and the head passed inwardly through the slot in the outer end of the socket and then again turned to its original and normal position, so that the neck may lie in the notch 8, with the enlarged head extending 10 transversely across the notch and in engagement with the inner upper portion of the socket, whereby the fastening is connected to the socket and the sash. By this means the 15 cord may be conveniently applied to and removed from the sash without damage to any of the parts and does not require the removal of other fastening devices.

The staggered relation of the ears 12 of the cord-fastening permits of the same overlapping a considerable portion of the cord, as adjacent opposite ears may project beyond each other without interfering, whereby a secure fastening is had between the shank and the cord.

25 The advantage of the present form of socket resides in the fact that it may be struck from a blank of metal, then bent into tubular form, and finally having the ears bent laterally into their normal position, thereby providing a 30 strong, durable, and inexpensive form of socket.

What is claimed is—

1. As a new article of manufacture, a sash-cord-fastener socket for window-sashes, consisting of a split-spring tubular socket having 35 its outer end closed and provided with a diametric slot, which terminates in a longitudinal slot or bifurcation in the socket.

2. As a new article of manufacture, a sash-cord-fastener socket for window-sashes, consisting of a longitudinally-split tubular socket having an open inner end and provided at its 40 outer end with opposite inwardly-directed

ears, which terminate short of each other to form a diametric slot, there being a longitudinal notch formed in the outer end of the socket at that end of the last-mentioned slot which is opposite the longitudinal split of the socket. 45

3. A sash-cord fastener, consisting of a 50 socket having its outer end provided with a diametric slot terminating at one end in a longitudinal notch in one side of the socket, and cord-engaging fastening having a shank, provided at opposite longitudinal edges with 55 staggered bendable ears, a reduced neck at its normally lower end, an enlarged head at the outer end of the neck and in substantially the plane of the shank, and spurs struck from the shank, lying upon the inner side thereof, 60 and inclined outwardly and downwardly toward the head, the latter being adapted to be entered into the socket through the end slot thereof.

4. As a new article of manufacture, a sash-cord-fastener socket, formed from a single blank which is bent into a longitudinally-split spring tubular socket, one end edge of the blank having projected ears which are bent laterally inward in opposite directions across 70 one end of the socket and terminated short of each other to form a diametric slot, the adjacent end edge of the socket being provided with a longitudinal notch located diametrically opposite the longitudinal split of the 75 socket and at the adjacent end of the diametric end slot.

In testimony that we claim the foregoing as our own we have hereto affixed our signatures in the presence of two witnesses.

JAMES C. BARR.
VIRGIL EDSON BARR.
